UNITED STATES PATENT OFFICE.

WILLIAM A. CHRYSST, OF DAYTON, OHIO, ASSIGNOR TO THE DAYTON ENGINEERING LABORATORIES CO., A CORPORATION OF OHIO.

BINDING-POST.

1,193,513.

Specification of Letters Patent. Patented Aug. 8, 1916.

Application filed January 6, 1913. Serial No. 740,437.

To all whom it may concern:

Be it known that I, WILLIAM A. CHRYSST, a citizen of the United States, residing at Dayton, county of Montgomery, and State of Ohio, have invented certain new and useful Improvements in Binding Posts, of which the following is a full, clear, and exact description.

This invention relates to an improvement 10 in terminal or binding posts and has for one of its objects to provide a device of this character, which will support a plurality of terminal clips or wires.

A further object of this invention is to 15 so combine the elements thereof, that the structure will be simple and compact, and especially adaptable to be used in places, wherein economy of space is desired or essential.

20 With the above and incidental objects in view, there is shown in the accompanying drawings, a preferred form of one embodiment of my present invention, a detail description of which will now be given.

25 In the drawings: Figure 1 is a vertical sectional view of a binding post embodying the present invention, taken on the line 2—2 of Fig. 2. Fig. 2 is a view in side elevation of a binding post embodying the present invention. Fig. 3 is a sectional view of a modified form of the present invention. Fig. 4 is a detail perspective view of the terminal clip.

30 Referring to the drawings: Figs. 1 and 2 discloses a binding or terminal post which is adapted to receive electrical connections which are to be insulated from each other, while in Fig. 3, there is shown a terminal post which is adapted to form a part of the 40 circuit to which the terminals, secured to the post, are a part.

In Figs. 1 and 2, it will be seen that the binding post comprises a central rod or stud 20, having a flange or projection 21, formed intermediate the ends thereof and providing a base for the spring pressed cap or sleeve 23, of the upper clamping element or binding post. This cap or sleeve is counterbored, as at 24, and has the spring 25, seated in the counterbored portion. A shoulder, formed by counterboring said sleeve, acts as one abutment for the spring 25, and the plate 26, which is secured to the extremity of the stud 20, constitutes the opposite 55 abutment. From this construction, it will

be seen that the spring 25 normally maintains the cap or sleeve 23 in contact with the flange 21.

The binding post structure disclosed herein is adapted to receive a specially constructed clip, which may be fastened to the end of a wire or conductor, which is to be secured to the binding post. This terminal clip comprises a shank portion 29, provided with a head 30, wherein an annular opening 31, 65 having an entrance opening 32, is formed.

In order to secure the terminal clip 28 against accidental removal from its applied position, the diameter of the opening 31 is made slightly greater than the diameter 70 of the locking shoulder 27, but less than the diameter of the flange 21, while the diameter of the entrance opening 32 is greater than the diameter of that portion of the stud 20, which is surrounded by the sleeve 23, but is 75 less than the diameter of the locking shoulder 27.

In Figs. 1 and 2, there is shown an additional clamping element. This clamping element is insulated from the structure here- 80 fore described, so that an electrical connection may be made, which may be absolutely insulated from and independent of the electrical connection secured by the outer clamping element.

85 The central stud 20 is in the present instance surrounded by an insulated sleeve 41, which has at one end, the washer or head 42, one face of which lies adjacent to the washer 21. The opposite face of this washer 42 90 carries a metal facing 44, which forms a bearing element for the reduced end 45 of the movable sleeve 46. A metal tube 47, surrounds a portion of the said sleeve 41, and is reduced as at 48, thus forming the shoulder 49, which furnishes one abutment for the spring 50. This spring is mounted in the reduced portion of the metal sleeve 47, and tends to normally maintain the movable sleeve 46 in contact with the metal facing 44 of the washer 42. The movable sleeve or clamping element 46 has an internal flange, as at 51, which forms an abutment, against which the spring normally presses, whereby this sleeve, as above stated, is maintained in 100 contact with the metal facing 44 of the washer 42. The shoulder 52 is formed on the movable sleeve 46, and tends to normally maintain the movable sleeve 46 in contact with the metal facing 44 of the washer 42. The movable sleeve or clamping element 46 has an internal flange, as at 51, which forms an abutment, against which the spring normally presses, whereby this sleeve, as above stated, is maintained in 105 contact with the metal facing 44 of the washer 42.

In a binding post of this type, a locking shoulder 52 is formed on the movable sleeve or clamping element, by reducing the clamp- 110

ing end thereof, as at 45, so that the terminal clip which is used in conjunction with this portion of the binding post, must have its main opening of greater diameter than the reduced portion of the sleeve, while the entrance opening must be of less diameter than the diameter of the reduced portion 45, but of greater diameter than the cross sectional diameter of the metal tube, upon which the movable sleeve is mounted, and which in reality forms the electrical connection.

- In Fig. 3 there is shown a modified form of the binding post illustrated in Figs. 1 and 15 2. This modified structure shown in Fig. 3, comprises a terminal post of conductive material, whereby the respective terminals connected thereto, may have a common electrical connection with any circuit to which the 20 body of the binding post may be connected with. The structure of the post shown in Fig. 3 comprises a central stud, having a projection or flange 55, provided with a locking shoulder 56.
- 25 The co-operating clamping element 23, its controlling spring 25, and the plate 26, are substantially the same as the corresponding elements heretofore described in connection with Fig. 2. The arrangement of the lower clamping element 57, however, is directly mounted on the shank of the stud 20, and is maintained in clamping position, relative to

the end face of the flange or projection 55, by means of the spring 50. One end of the said spring 50 abuts against the shoulder formed by the element 58, which is secured to the threaded extremity 59 of the stud 20.

30 While I have shown preferred forms of embodiment of the present invention, it should be understood that various changes and modifications of the elements and combinations of elements, comprising the present invention, may be made without departing from the spirit and scope of the present invention.

45 What I claim is as follows:

In a binding post, the combination with a plurality of movable clamping elements; of a supporting stud of conductive material having a shoulder co-operating with one of 50 said clamping elements; an insulating sleeve separating said stud from the conductive elements of the other clamping element, whereby independent circuit connections may be made with each of said clamping elements 55 and independent spring means operable relative to said movable clamping elements to maintain the same in clamping position.

55 In testimony whereof I affix my signature in the presence of two subscribing witnesses.

60 WILLIAM A. CHRYST.
